UNITED STATES PATENT OFFICE.

THEODORE HINOULT, OF ALBANY, NEW YORK, ASSIGNOR TO MARY IDA
HINOULT, OF SAME PLACE.

DESIGN FOR A COVER FOR FRYING-PANS.

SPECIFICATION forming part of Design No. 31,464, dated August 29, 1899.

Application filed May 11, 1899. Serial No. 716,443. Term of patent 14 years.

To all whom it may concern:

Be it known that I, THEODORE HINOULT, a citizen of the United States, residing at Albany, in the county of Albany and State of New York, have invented and produced a new and original Design for Covers for Frying-Pans, of which the following is a specification, reference being had to the accompanying drawings, forming a part thereof, in which—
10 Figure 1 is a view of the cover from its upperside, and Fig. 2 is a section of the same.
As shown in the drawings, the leading or material features of my design consist of a straight-line tapering form of side wall A
15 and a perforated circular flat top B, which is bordered all around by the plain flat margin C, which is uniformly projected to a low elevation above the plane of the top surface of the said perforated flat top B. The straight-

line tapering side wall A terminates all around at its base with a vertically-curved portion a, having the appearance from its lower side of a bead and from its upper side that of a groove and bordered all around by the flat horizontal and concentric rim D, all as shown.

This design may be embodied in covers made of any suitable material and in various sizes.

Having described my invention, what I claim as new, and desire to secure by Letters Patent, is—

The design for a cover for frying-pans as herein shown and described.

THEODORE HINOULT.
